SWITCHING SYSTEM

Etienne G. Alizon, La Celle-Saint-Cloud, France

Application January 31, 1951, Serial No. 208,794

Claims priority, application France April 6, 1949

11 Claims. (Cl. 179—18)

1

The present invention relates to switching systems operating on the capacitive test principle, and more particularly to means employed with such systems permitting the identification of a preselected frequency with one of a plurality of frequencies as a step in the establishment of a desired configuration of the switching system. The present application is a continuation in part of my copending application Serial No. 153,594 filed April 3, 1950.

The invention has especial application in automatic telephone exchanges, and will be described in connection with such use, although it is not restricted thereto.

In my said copending application there are described rotary selector switches in which the selection of a chosen outgoing line is effected without galvanic contact either between the scanning brushes of the selector rotor and the fixed contact pins of the stator or frame which are connected to the selector outgoing lines, or between the movable contacts connected to these brushes and the fixed contacts of the selector incoming line.

In such selectors the contact pins of at least one row in the frame are held at electric potentials of different frequencies according to their azimuth. In the course of a switching operation the rotor scanning brush which sweeps past these pins without contact therewith, forms successively with each such pin a variable condenser and thus experiences successive pulses of voltage having frequencies characteristic of the different outgoing lines. Although for simplicity they will be so described, these "pins" are preferably not pins at all, but are shaped like condenser plates. Neither are they contacts in the usual sense, since no galvanic contact is made therewith. They function rather as plates or electrodes of condensers.

The pulses are transmitted, via the condenser formed by a rotor contact connected to the rotor scanning brush and by a stator contact connected to a wire of the selector incoming line, to an identifying device charged with interrupting the motion of the rotor upon the receipt of an impulse of a predetermined frequency. At the moment of stopping, the rotor of the selector undergoes a translation in the direction of its axis and applies certain other brushes against the actual stator contact pins of the selected outgoing line. Likewise the rotor contacts connected to the scanning brushes are applied against the stator contacts connected to the incoming line. The capacitive connection furnished by the selector is thus made galvanic.

In view of cabling considerations which dictate a disposition of the pins of a given outgoing line along a single direction parallel to the axis of the selector rotor and in view of the time interval necessary for identification of the frequencies and stoppage of the selector, it is advantageous to advance the brushes which make the capaci-

2

tive tests by one or more azimuth intervals by reference to the other rotor brushes which are to make galvanic contact with the pins of the stator. In the traverse of the angular spacing separating these two azimuths there is made available the time necessary for the rotor to stop.

The present invention has for an object the provision of identification means operating on the successive pulses of voltage of different frequencies picked up by the scanning brushes of an associated selector and on a voltage of the characteristic frequency of the desired outgoing line. This characteristic frequency is chosen and made available to the identification means by a signal storage or recording device referred to in the telephone art as a sender. The identification means of the invention then stops the selector when the two frequencies which it receives are the same.

Such an identification means is composed essentially of two electron tubes operating as clippers to clip into square wave form the alternating voltages picked up by the scanning brushes of the selector and the alternating reference voltage provided by the sender, and of an electron tube for mixing these two voltages. The mixing stage includes in its plate circuit a linear resistance in parallel with a series combination of a condenser and a non-linear resistance. This parallel combination has two time constants according to the direction of the current flowing through it. As will be more fully explained below such a circuit produces in the mixing stage a plate voltage drop which is substantially zero when the two voltages applied to the mixer are of different frequencies and which on the contrary is substantial when these two voltages are of the same frequency and of opposite phase. The voltage pulse produced at the instant of coincidence of the two frequencies is used to stop the rotation of the selector rotor.

By reason of the dimensions customarily given to the contact pins of the fixed banks of such selectors, the capacity of a condenser formed by a scanning brush and a pin is small by comparison with the capacity of the condenser formed by the rotor contact connected with the scanning brush and the fixed contact connected to the incoming line, and also by comparison with the capacity between the conductors of the incoming line and ground. The result is a substantial attenuation in the voltage pulse picked up by the scanning brush. Consequently the invention provides for the identifying means amplifiers suitable to amplify the voltage pulses successively picked up by the scanning brushes.

In order to prevent stopping the selector on a chosen outgoing line if that line is busy, a separate scanning brush of the rotor tests capacitively for each output line a special contact pin which is held at an alternating voltage of special frequency when that line is busy. The voltage impulse picked up by this brush, when the desired

line is busy, is amplified and detected, and the detected voltage serves to neutralize the stopping impulse generated by the selector and identifying means for the outgoing line in question.

For reasons of economy and compactness it is desirable to be able to associate a single identification means with the selectors of a number of successive selector stages cooperating in the establishment of a communication circuit. These selectors are then held engaged by energization of their stopping coils in parallel through a busy circuit extending throughout the complete chain of selectors.

In the event that two selectors operating toward the establishment of different communication circuits come into conflict on a single line, there occurs a double or duplicate test or selection (i. e. with affirmative response) which, if allowed to be completed, must then be canceled by a complete disestablishment of the switching chains up to and including the selectors so doubly connected to a single line. This follows necessarily because the identification of the line on which conflict occurs is effected by each selector without galvanic contact between its brushes and the stator pins of that line, in consequence of which recognition of the double selection is impossible before completion of the circuit and further by virtue of the fact that the holding coils of all selectors in the cascade establishing a single communication circuit are connected in parallel on the same busy condition wire.

The invention consequently provides means which systematically prevent the occurrence of duplicate selections. Upon the operation of an identification means coupled with a selector of a given stage, such selector being at a given azimuth, these means for the prevention of duplicate selection disable other identification means coupled to those selectors of the same stage which are indexed to azimuths characterized by the same frequency as the azimuth of the first selector. In the event that two identification means operate to disable each other mutually, i. e. in the event of incipient duplicate selection, a balancing effect occurs which ultimately produces a complete functioning of one of these identification means and the disablement of the other.

The invention will be better understood by reference to the following detailed description taken in conjunction with the accompanying drawings in which:

Fig. 1 is a schematic diagram of a selector switch of the capacitive test type, showing the rotor contacts and brushes thereof and the contacts of one azimuth interval of the stator.

Fig. 2 is a partial view of a selector switch of the type schematically shown in Fig. 1, Fig. 2 being taken in the direction of the axis of the switch rotor.

Fig. 3 shows schematically two multiplied selectors.

Fig. 4 is a schematic diagram of an identification means according to the invention.

Fig. 5 is a representation of certain voltage wave forms appearing in the circuit of Fig. 4 on the assumption that the two voltages applied to that circuit are of different frequencies, and

Fig. 6 is a representation similar to that of Fig. 5 but illustrating the corresponding wave forms in the event that the voltages applied to the identification means are of the same frequency.

Referring now to Fig. 1, the stator of the selector comprises a panel of pins providing two outgoing lines per azimuth. With each outgoing cir-

cuit there are associated seven pins thus making fourteen outgoing line pins per azimuth. These include three pins or electrodes of flat plate form 37, 137 and 237 for the first outgoing line and 37', 137' and 237' for the second. The pins of flat plate form constitute variable condensers with the scanning brushes of the rotor. In addition there are required for the galvanic contacts four round pins, 38, 138, 238 and 338 for the first outgoing line and four similar round pins 38', 138', 238' and 338' for the second. These round pins come into galvanic contact with the corresponding brushes of the rotor upon the axial translation of the rotor when it is brought to rest.

The stator further includes four rings 31, 131, 231 and 331 (which may be of semicircular shape as described in my copending application above referred to) and four contact blades 32, 132, 232 and 332. Each ring and its corresponding contact blade are connected to one of the wires a, b, t and o of the incoming line. The stator rings form condensers with corresponding rings of the rotor, all being concentric in the axis of rotation of the rotor, and the contact blades come into contact with these rotor rings upon the translation of the rotor. In addition, upon such translation, the blades 232 and 332 respectively break and make contact with the fixed blades 233 and 333 upon this translation.

Of the four wires a, b, t and o of the incoming line, a and b are the talking conductors, t is the test wire and o is the busy wire.

The selector rotor includes rings 41, 141, 241 and 341, mounted concentrically in its axis of rotation. The first three of these are connected each to the members of two diametrically opposite and suitably axially displaced pairs of brushes, viz. 50, 51 and 50', 51' for the ring 41; 150, 151 and 150', 151' for the ring 141; and 250, 251 and 250', 251' for the ring 241. Those having reference characters which are multiples of 10 are scanning brushes while the others are for the establishment of galvanic contact. The ring 341 is connected only to two diametrically opposite brushes 351 and 351'. The brushes 50, 150, 250 and 50', 150', 250' are of flat shape, whereas the brushes 51, 151, 251 and 51', 151', 251' are provided with spades or lips as shown at 80.

The unprimed rotor members scan and make contact with one half of the outgoing lines led to the selector, viz. the upper line for each azimuth, and the unprimed members, which are axially displaced from their unprimed counterparts, cooperate similarly with the remaining outgoing lines, of which one occupies the lower position in the stator for each azimuth.

Whether the selector is idle or operating to establish a circuit, its rotor turns continuously with its incoming line rings 41, 141, 241 and 341 rotating respectively adjacent the rings 31, 131, 231 and 331 of the stator. In the azimuth of the stator shown, the scanning brushes 50, 150 and 250 rotate past the flat stator pins 37, 137 and 237 of one outgoing line and the scanning brushes 50', 150' and 250' rotate past the flat stator pins or electrodes 37', 137' and 237' of the other outgoing line. The lipped or curled rotor brushes 51, 151, 251 and 351 rotate past the round stator pins 38, 138, 238 and 338 of one outgoing line and the lipped rotor brushes 51', 151', 251' and 351' rotate past the round pins 38', 138', 238' and 338' of the other outgoing line, all without galvanic contact between the rotating and the stationary elements.

In the course of a selection operation the scan-

ning brushes 50, 150 and 250 (or 50', 150' and 250') of the rotor are moving past the flat pins 37, 137 and 237 (or 37', 137' and 237') of all the azimuth positions of the stator. Of each set of three stationary contacts at least one contact is held at an alternating voltage of frequency characteristic of the outgoing line to which it belongs. Consequently one or more of the flat brushes 50, 150, 250, or 50', 150', 250' pick up successive voltage pulses which are transmitted to the identification means which form the object of the present invention.

When the identification means receives and responds to that one of these successive pulses whose frequency is equal to a preselected frequency, a pulse is passed from the identification means through the wire *t* and via contacts 232 and 233 to energize the coil 35. The time of operation of the identification means and of the selector itself are so adjusted that the rotor of the selector executes a combined rotation and translation (in the sense of the arrow 81) imposed upon it by the pulse last referred to and stops with the lips 80 of its brushes 51, 151, 251 and 351 in contact with the round pins 38, 138, 238 and 338 (or similarly as to primed elements in the event the pulse of frequency equal to the preselected frequency is picked up from one of the contacts 37', 137' or 237').

Simultaneously the rotor rings 41, 141, 241 and 341 come into contact with the stator blades 32, 132, 232 and 332. The contact previously existing between 232 and 233 is opened by the pressure of 241 against 232 and contact is similarly made between 332 and 333, 233 and 333 being in the stator. Galvanic octant is thereby established between the wires *a*, *b*, *t* and *o* of the incoming line, and the wires A, B, T and O of the outgoing line. The wires of the second outgoing line for the azimuth shown corresponding to A, B, T and O connecting respectively with 38', 138' 238' and 338'—237' have been omitted for simplicity, as have been the wires thereof corresponding to S' and S.

Fig. 2 shows a view in plan of a selector, assumed to be a final selector. Fig. 2 shows a two interval difference in azimuth between the brushes 150 and 151 and a one interval difference in azimuth between the brushes 50 and 51. The selector illustrated identifies the desired outgoing line first as to a frequency characteristic of the tens digit and then as to a frequency characteristic of the units digit of that line. The tens digit identification is first and therefore the scanning brush 150 which scans the stator contacts 137 to which the tens digit frequencies are applied is two azimuth intervals in advance of the rotor galvanic contacts 51, 151, 251 and 351. The brush 50 which scans the units digit contacts 37 is only one azimuth interval in advance of the rotor galvanic contacts.

Of course Fig. 2 is illustrative only; these azimuthal separations depend upon the time necessary to stop the rotor, having due regard to its speed of rotation.

Fig. 3 shows in simplified form and again for a single azimuth, two final selectors of the type of Fig. 1, multiplied together. The condensers respectively formed by the rings 31 and 41, 131 and 141, 231 and 241 and by 331 and 341 (Fig. 1) are of large value compared to the variable condensers respectively formed by the brushes and pins 50 and 37, 150 and 137 and 250 and 237. They may therefore be neglected in a series connection. Consequently in Fig. 3 the incoming line of each

selector has been shown with its wires *o*, *t*, *a* and *b* directly connected to the scanning brushes 50, 150, 250 and to contact 351.

The outgoing lines are distributed over fifty separate geometrical azimuths of the stator with two lines per azimuth. The fifty azimuths may for example occupy approximately a semicircle as set forth in my copending application Serial No. 153,594. To each stator azimuth there correspond two diametrically opposite sets of brushes in the rotor, by one of which the selector incoming line can be connected to one of the outgoing lines of that stator azimuth and by the other of which the incoming line can be connected to the other outgoing line of that stator azimuth. There are accordingly one hundred relative azimuthal positions of the rotor and stator, each belonging to one of the selector outgoing lines. The selector will therefore be said to have one hundred azimuths.

Let it be assumed for example that each final stage selector gives access to one hundred outgoing lines numbered from 00 to 99 and that ten alternating voltages of frequencies F_0 — F_9 are available. Let it be further assumed that for a given azimuth of the selector, azimuth 36 for example, the alternating voltage F_3 proper to the digit 3 is connected from the sender for example to the wire S' representing the decades and that the frequency F_6 proper to the digit 6 is connected to the wire S representing the units.

The group selectors are identical to the final selectors but in general comprise only one selection wire S' for example, inasmuch as in general they have ten groups of outgoing lines or less. It is however to be understood that it is possible to effect with such group selectors selections at two or more characteristic frequencies.

The multiplying wires A, B, T and O of an outgoing line of a group selector are respectively connected to the wires *a*, *b*, *t* and *o* of the incoming line of a selector of the following stage.

When the selector is stopped at the desired outgoing line by operation of the short pulse produced in the wire *t* as explained above, a battery permanently connected to the busy wire *o* keeps the selector stationary and engaged by feeding the winding 35 through the normally open (now closed) contact between 332 and 333 and through an economizer resistance 34. To the voltage of this battery there is added an alternating voltage of a special frequency which is therefore applied through the brush 351 to the pin 338 and consequently to the busy wire O of the chosen outgoing line. This voltage therefore indicates the busy condition of the outgoing line chosen by the selector.

The operation of the frequency identification means will be described with reference to Fig. 4. It will be described in connection with the selection of a chosen outgoing line by means of a final selector.

In Fig. 4, 401 represents a calling subscriber's station. 402 represents the pulse contacts of his calling dial, and 403 is his subscriber's line. The dashed-line box indicated generally at 4 is the recording means or sender which, from the impulses received from the calling subscriber's dial, generates or selects the frequencies characteristic of the line called. Let it be assumed that the desired characteristic frequencies are f_d for the decades digit and f_u for the units digit of the called line. 404, 405, and 406 are respectively the counting relay, the busy relay and the relay associated with the end of the impulse train, the latter two

being delayed in release. According to well-known methods of operation relay 405 is energized as soon as 404 is energized and remains energized during the dialing. 406 remains energized during the transmission of one digit and reopens at the end of the train of impulses corresponding to that digit.

407, 408 and 409 are step by step rotary switches having eleven azimuths. The switch 407 operates to select the test frequencies appropriate to the successive digits dialed. It advances through one step at each deenergization of the relay 406 (opening of normally open contact 4061) at the end of each digit dialed. Consequently it directs the ground impulses, which reach its brush through the normally open contact 4051 and through the normally closed contact 4031, first toward the tens frequency selector 408a and then the units frequency selector 408u.

The stator pins of the selector 408a and of the first row of contacts in selector 408u are connected to ten sources of alternating voltage (not shown) of different frequencies of f_6-f_9 . At the end of dialing the brush of 408a will be positioned in a particular azimuth corresponding to the tens digit and the brush of 408u will be positioned in a particular azimuth corresponding to the units digit. There then appears therefore on wire 410 the frequency f_4 proper to the tens (f_3 in the figure) and, on wire 411, the frequency f_4 proper to the units (f_6 in the figure).

The selector 409u is provided with a second row of pins marked from D_{t_0} to D_{t_9} which are multiplied to all units selectors such as 408u.

The characteristic test frequency f_4 of the decades digit is transmitted through the normally closed side of contact 4161 on relay 416 to the input of a resistance-coupled thermionic amplifier 2 including a pentode 414 whose output is applied to the grid of a clipper stage 4 including a triode 418.

In the course of the rotation of the final selector rotor the potentials of different frequencies picked up by its brush 150 (Fig. 1) are transmitted by the wire b (see now Fig. 4) via the normally closed side of contact 4162 (as shown) on relay 416 to the input of a resistance-coupled thermionic amplifier 3 including two pentodes 415 and 417. The output of tube 417 is applied to the grid of a clipper stage 5 including a triode 419.

The clipper stages 4 and 5 preferably take the form of the two halves of a double triode, tubes 418 and 419 being thus combined in a single envelope.

The variable condenser formed by the brush 150 in passing in front of a flat plate contact such as 137 (Fig. 1) possesses a small capacity by comparison with the capacity between ground and the wire b connecting this brush 150 to the input resistance 413 of the amplifier 3. The result is that the potential across this input resistance is substantially cophasal with the alternating voltage source which feeds the contact pin 137.

When the voltage applied to the input of the amplifier 2 is of the same frequency as that applied to the input of the amplifier 3, these two voltages are in phase, e. g. in view of their origin in a common source permanently coupled to the test wire S or S' of the proper outgoing line or lines, the same source being tapped by the applicable comparison frequency selector 408a or 408u. The voltages at the outgoing terminals 420 and 421 of the clipper stages 4 and 5 are consequently in phase opposition since one has

undergone a single amplification in 2 and the other two amplifications in 3. Of course other means may be availed of to bring the voltages at the output of the amplifiers 2 and 3 into phase opposition, when of the same frequency, if desired.

The output voltages of the clipper stages 4 and 5 are applied to a mixing stage 6 including a pentode 428. In tube 428 the voltage at the point 424 is applied to the control grid 423 and that at 420 to the suppressor grid 422. Both of these grids are operated at zero bias, and the tube can be cut off on either grid by the negative swing of the voltage applied thereto from the clipper 4 or 5 which is coupled thereto. The plate circuit of tube 428 includes a linear resistor 429 in parallel with a series combination of the condenser 430 and a non-linear resistor 431. These three elements together constitute a circuit generally indicated at 7 which has two time constants. In a preferred embodiment the condenser 430 is adjacent the source of B+ voltage HT, and the non-linear resistor 431 is adjacent the mixer tube plate. Moreover the larger of the two resistance values of 431 is preferably large compared to the resistance of 429. The non-linear resistance is poled to offer a low resistance to current flowing through it toward the mixer tube plate and to offer a large resistance to current flowing through it toward the condenser. When the charging current for the condenser 430 flows from the junction 433 toward the junction 434 the time constant of the circuit 7 is of low value. When the charging current flows from 434 toward 433, this time constant is large. More specifically, the circuit 7 is preferably so established that its short time constant is short compared to the period of all test frequencies which may be applied to the amplifiers 2 and 3, and its long time constant is long compared to the period of these frequencies.

When the identification circuit is quiescent, i. e. when no voltages are applied to the grids 422 and 423 of tube 428, this tube conducts and the plate current flowing through the resistance 429 produces a drop between points 433 and 434, bringing the point 434 to a given voltage V_0 .

When the identification circuit is in operation the voltage of the point 425 remains close to the value V_0 if the two frequencies applied to tube 428 are different. On the other hand the voltage of the point 425 shifts to a higher value V_1 corresponding to cut-off of the tube 428 if the two frequencies applied to it are the same, as will now be described.

The terminal 425 at the output of the two-time constant circuit 7 is connected to the input of a trigger means shown as a monostable multivibrator 8 including a normally non-conducting pentode 435 and a normally conducting triode 438. The terminal 425 is connected to the screen grid 437 of tube 435. This tube is cut off when the voltage of its screen grid is V_0 , and it conducts when this voltage is V_1 . The onset of plate current in tube 435 at the instant when the voltage of the terminal 425 reaches the value V_1 produces reversal of the conduction phase in the multivibrator. Tube 438 then remains cut off, and tube 435 conducts, during a specified time interval depending upon the time constants of the various circuits connected to these tubes. The result is a positive pulse at the output terminal 441 of the multivibrator. This pulse is transmitted through the normally closed side of contact 4163 to the plate of cold cathode tube

439 which thereupon comes into conduction, energizing the relay 416.

The circuit generally indicated at 9 including the cold cathode tube 439 and the relay 416 constitutes a switch which causes the identification means to pass from the decades circuit to the units circuit. By operation of the normally open sides of contacts 4161 and 4162, now closed, the grids of tubes 414 and 415 in amplifiers 2 and 3 are now respectively connected to the wire 411 and to the wire a . Wire 411 is energized at the frequencies f_u proper to the units digit of the desired line and the wire a is connected to the brush 50 (Fig. 1) of the final selector whose operation is being considered.

In the manner described above the motion of the brush 50 past the pin 31 energized at the frequency f_u causes a positive voltage pulse to appear at the outgoing terminals 441 of the multivibrator 8. This pulse, passing through the normally open side of contact 4163 (now closed) brings into conduction the tube 442 in amplifier 10, which functions as a stopping-pulse generator for the selector rotor. As shown, tube 442 is biased off in the absence of signal. At the junction 443 in the cathode circuit of amplifier 10 there then appears a positive pulse which is applied to the wire t of the incoming line via the wire 424. This impulse then passes via elements 232 and 233 (Fig. 1) to the stopping coil 35 of the final selector under consideration. As previously explained, the selector rotor then undergoes translation in the direction of the arrow 81 (Fig. 1). Contact is interrupted between 232 and 233 and established between 322 and 333. The coil 35 is maintained energized by the battery applied to the wire o .

If the line requested is busy, the brush 250 of the selector picks up in moving past the flat electrode pin 237 of this line a voltage of a frequency characteristic of the busy condition. This voltage is applied to the pin 237 of the selector which is hunting, i. e. that under consideration from a source 427 (Fig. 4) via the transformer 426, wire o and contacts 332 and 333 of the selector which is stopped on the line desired (i. e. another selector in use in the circuit previously established) and the multiplying wire O . It is transmitted via the wire t of the selector which is hunting, the line 424 (Fig. 4) and normally open contact 4164 (now closed) to the input of a busy condition signal amplifier-detector 11 (Fig. 4).

The amplifier-detector 11 includes pentodes 445 and 446 coupled to a rectifier 449 by transformers 447 and 448 which are tuned to the busy signal frequency. The outgoing signal from the tube 446 is rectified by the bridge rectifier 449 in conjunction with the resistance 450 and condenser 451 and the positive rectified voltage is applied to the control grid 453 of a pentode 452 which is normally cut off through 450 in the absence of such rectified voltage. Consequently if the desired line is busy, tube 452 is brought into conduction and a negative pulse appears in its plate circuit at 454 and is transmitted by the wire 460 to the suppressor grid 436 of tube 435 in the multivibrator circuit 8. Tube 435 is accordingly blocked and the arrival of a positive pulse from the terminal 425 no longer causes a phase reversal in the multivibrator. Consequently no pulse appears at the output terminal 441 of the multivibrator nor at 443 and the selector does not stop at the occupied line.

It has been explained how the unbiasing of tube 442 produced a positive pulse on its cathode

at 443 with resultant stopping of the selector. Simultaneously a negative pulse appears at junction 444 in the plate of tube 442. This pulse is transmitted via line 451 to the suppressor grid 455 of pentode 452 and to the control grid 459 of triode 458. This triode constitutes an amplifier 12 for the suppression of duplicate selections.

The negative pulse originating at the plate of amplifier 10 cuts off tube 452. With 452 so cut off the positive pulse formed at the cathode 443 of amplifier 10 and transmitted to the input of amplifier 11 is unable to bring tube 452 into conduction even though applied to its grid 453. Consequently neutralization of the operation of the multivibrator is prevented.

The same negative pulse from the plate of the tube 442 similarly cuts off tube 458. 458 consequently sends a positive pulse through the normally open contact 4165 (now closed) to the multiplying line D_t multiplied to the pins of the second bank of all selectors 409_u of all senders (in the figure to the wire D_{t_0}).

Therefore, during the occurrence of a positive stopping pulse sent by the tube 442 to line 424 and to wire t , (i. e. as the result of a prima facie successful identification or selection) tube 452 receives a negative pulse on its suppressor grid 455 via line 451, a positive pulse on its control grid 453 via line 462, and a positive pulse on its screen grid 456 via line 461 (from the plate of 458). The magnitudes of these pulses are adjusted so that the tube 452 remains non-conducting during their occurrence.

The tubes 452 of other identification means operating at the same moment to effect final selection of a line having the same units digit are unblocked by the pulse arriving over the corresponding line D_t . There results a blocking of the tubes 435 of their associated multivibrators, preventing the identification circuits from bringing about a stopping of their associated selectors during the occurrence of the said pulse. The final selector under consideration is therefore able to effect selection of the desired outgoing line.

If two identifying circuits simultaneously cause their selectors to stop on lines having the same units digit, there results either a mutual blocking and prevention of either identification circuit from effecting its stoppage if the circuits above described are of exactly the same characteristics, or else, as will usually be the case, these characteristics will not be identical and there will be a balancing of unequal circuits, one of the identification circuits causing a stoppage and disabling the other identification circuit.

The operation of the identification circuit will now be explained.

In Fig. 5 there are shown as functions of time: At A, the sinusoidal voltage applied to the input resistance 412 of the amplifier 2;

At B, a sinusoidal voltage, of frequency assumed different from that of A, applied to the input resistance 413 of the amplifier 3;

At C, the output voltage of the amplifier 2;

At D, the output voltage of the amplifier 3;

At E, the voltage at the output terminal 420 of the clipping stage 4;

At F, the voltage at the output terminal 421 of the clipping stage 5;

At G, the voltage of the junction 434; and

At H, the voltage at the terminal 425 at the output of the two-time constant circuit 7.

The voltage G is equal to V_1 when the tube 423 is cut off, i. e. when at least one of the two grids 422 and 423 is sufficiently negative. This will

be true at any time during the existence of either the pulse 501 of voltage E or the pulse 502 of voltage F. The voltage G at junction 434 is equal to V_0 when the tube 428 is conducting, i. e. when the potentials of the two grids 422 and 423 are simultaneously at or close to zero. This will be true at any time during the co-existence of the pulse 503 of voltage E and of the pulse 504 of voltage F.

When the voltage G changes from the value V_0 to V_1 , the charging current of the condenser 430 flows from 434 towards 433, and the voltage H increases relatively slowly since the time constant of the circuit 7 is large for this direction of charging current. This corresponds to the portion 505 of voltage wave form H. When the voltage G passes from the value V_1 to V_0 , the charging current flows from 433 to 434, and the voltage H declines relatively quickly since the time constant of the circuit 7 is then small. This is represented by the portion 506 in wave form H. In consequence of the shape of wave form H, as long as the brush 150 for example is passing in front of the pins 137 for azimuths energized at frequencies different from the frequency f_a , tube 428 will be successively cut off and allowed to conduct in a variable time sequence depending upon the relative values of the said frequencies. In view of the dissymmetry of the time constants of the circuit 7, the voltage at the terminal 425 which is represented by the peaks of the wave form H will remain close to V_0 .

In Fig. 6 there are shown as functions of time:

At A', a sinusoidal voltage applied to the input resistor 412 of amplifier 2;

At B', a sinusoidal voltage assumed of the same frequencies as that of A', applied to the input resistor 413 of amplifier 3;

At C', the output voltage of amplifier 2;

At D', the output voltage of amplifier 3;

At E', the voltage at the output terminal 428 of the clipper stage 4;

At F', the voltage at the output terminal 421 of the clipper stage 5 (this voltage is now permanently in phase opposition with the voltage E');

At G', the voltage at the junction 434 in circuit 7; and

At H', the voltage at the output terminal 425 of the two-time constant circuit 7.

Since under these conditions at least one of the two grids 422 or 423 is always strongly negative, the tube 428 is permanently cut off. The voltage G' is fixedly equal to V_1 . In Fig. 6 the slope 601 represents the passage of the voltage G' from the value V_0 to the value V_1 at the initial moment of identity in the frequencies of the voltages applied to the grids 422 and 423. The slope at 602 represents the passage of the voltage G' from V_1 to V_0 when this identity ceases.

When wave form G' changes at the time of slope 601 from the value V_0 to V_1 , the plate current flows from junction 434 to junction 433, and the voltage H' increases exponentially according to the longer of the two time constants of the circuit. As described in my copending application Serial No. 153,594, the lowest frequency employed for capacitive testing according to my invention has a period much shorter than the time required for the motion of the selector rotor scanning brush past the test pins or electrodes of the selector stator. Accordingly the time interval during which identity of frequencies is maintained is sufficiently long for the voltage H' to reach the value V_1 . This voltage V_1 is sufficient to effect phase reversal in the multivibrator 8.

It is to be understood that the embodiment of the invention above described is exemplary only and that modifications in the particular circuits described can be effected by those skilled in the art without departing from the scope of the present invention.

I claim:

1. In automatic switching equipment employing capacitive testing in line finding, means to detect identity in frequency between an A. C. voltage of a particular frequency characteristic of a desired line and one of a succession of A. C. voltages of different frequencies scanned from a plurality of lines including said desired line, said means comprising a multigrid electron tube having two of its grids operated substantially at zero bias, means to apply to one of said grids in succession square waves having respectively as repetition rates the frequencies of the A. C. voltages scanned from the said plurality of lines, means to apply to the other of said grids a square wave voltage having as repetition rate the frequency of the voltage characteristic of the desired line, the voltage applied to said other grid being 180° out of phase with that of the same repetition rate applied to the first of said grids, and a parallel circuit connected between the plate of said multigrid tube and the source of plate voltage therefor, said circuit including a nonlinear resistor and a capacitor in series in one leg thereof and a resistor in the other leg thereof, said nonlinear resistor being disposed between said plate and capacitor and being poled to permit a rapid charging of the capacitor during conduction in said tube but to retard discharge of the capacitor when said tube is cut off.

2. In automatic telephone switching equipment employing capacitive testing for the identification of a desired outgoing line in a selector, means to identify an A. C. voltage of a given frequency picked up by a scanning brush of a selector with a cophasal A. C. voltage of the same frequency which is characteristic of a desired outgoing line of the selector, said means comprising means to invert the phase of one of the said voltages, means to clip each of said voltages into square wave shape, a multielectrode vacuum tube serving as a mixer, means to apply said voltages after clipping thereof and inversion of one thereof to separate grids of the mixer tube, a capacitor and a non-linear resistor in series connected in parallel with a resistor in the plate circuit of the mixer tube with the non-linear resistor between the tube plate and the capacitor, the nonlinear resistor being poled to permit a rapid charging of the capacitor during conduction in the mixer tube but to retard discharge of the capacitor when the mixer tube is cut off, whereby, upon coexistence at the grids of the mixer tube of identical frequencies for a time long by comparison with the period of either of said frequencies, the junction between the capacitor and the non-linear resistor rises to the plate supply voltage of the mixer tube.

3. In automatic telephony, in combination, a selector including an incoming line having a talking conductor and a busy test conductor; said selector further including for each of a plurality of outgoing lines connected thereto two fixed electrodes of which a first one is energized at an A. C. voltage of a frequency characteristic of its line and of which the second is energized when its line is busy by an A. C. voltage of a frequency characteristic of the busy condition; said selector further including a movable member, a first

scanning brush in the movable member forming with said first electrodes, upon motion of the member, capacitors for the transmission of the said line-characteristic voltages to the movable member, a second scanning brush in the movable member forming with the said second electrodes, upon motion of the member, capacitors for the transmission of the busy condition voltage to the movable member, means to transmit the voltages induced upon said first and second scanning brushes to the talking conductor and to the busy test conductor of the selector incoming line respectively; and line-finding apparatus comprising two thermionic amplifiers of which one provides to the signal passed therethrough substantially 180° more phase change than the other provides to the signal passed through said other, means to apply to one of said amplifiers the voltages appearing on said talking conductor, means to apply to the other of said amplifiers from a source cophasal with that employed to energize the first fixed electrode of a desired outgoing line a voltage of the frequency characteristic of the desired outgoing line, a clipping tube coupled to the output terminals of each of said amplifiers, a mixer tube having its control and suppressor grids operated at zero bias and capable of being cut off on either of its said grids, means to couple separately the clipping tubes to the control and suppressor grids of the mixer tube, a capacitor and a non-linear resistor in series connected in parallel with resistor in the plate circuit of the mixer tube, a monostable multivibrator, means to couple the junction between the capacitor and non-linear resistor to a grid of the normally non-conducting tube in the multivibrator, means actuated by reversal in the conduction phase of the multivibrator to initiate a stopping of the selector movable member, a tuned amplifier tuned to the busy condition frequency having its input coupled to the busy test conductor of the selector incoming line, and means coupled to the output of the tuned amplifier responsive to the appearance of a signal thereon to disable the multivibrator.

4. In automatic telephony, in combination, a selector including an incoming line having a talking conductor and a busy test conductor; said selector further including for each of a plurality of outgoing lines connected thereto two fixed electrodes of which a first one is energized at an A. C. voltage of a frequency characteristic of its line and of which the second is energized when its line is busy by an A. C. voltage of a frequency characteristic of the busy condition; said selector further including a movable member, a first scanning brush in the movable member forming with said first electrodes successively, upon motion of the member, capacitors for the transmission of the said line-characteristic voltages to the movable member, a second scanning brush in the movable member forming with the said second electrodes successively, upon motion of the member, capacitors for the transmission of the busy condition voltage to the movable member, means to transmit the voltages induced upon said first and second scanning brushes to a talking conductor and to the busy test conductor of the selector incoming line respectively, and line-finding apparatus comprising two thermionic amplifiers, means to apply to one of said amplifiers the voltages appearing on said talking conductor, means to apply to the other of said amplifiers a voltage of a frequency characteristic of a desired outgoing line, a multigrid mixer

tube capable of being cut off on either of two of its grids, means to couple separately the amplifier outputs to the said two grids of the mixer tube, a capacitor and a non-linear resistor in series connected in parallel with a resistor in the plate circuit of the mixer tube, a monostable multivibrator, means to couple the junction between the capacitor and non-linear resistance to a grid of the normally non-conducting tube in the multivibrator, and means actuated by reversal in the conduction phase of the multivibrator to initiate a stopping of the selector movable member, a tuned amplifier tuned to the busy condition frequency having its input coupled to the busy test conductor of the selector incoming line, and means coupled to the output of the tuned amplifier responsive to the appearance of a signal thereon to disable the multivibrator.

5. In a system of automatic telephony wherein each of a plurality of selectors includes an incoming line having a talking conductor and a busy test conductor; said selectors each further including for each of a plurality of outgoing lines connected thereto two fixed electrodes of which a first one is energized at an A. C. voltage of a frequency characteristic of its line and of which the second is energized when its line is busy by an A. C. voltage of a frequency characteristic of the busy condition, said selectors each further including movable means to scan capacitively the said electrodes of its lines and to transmit to a talking conductor and to the busy test conductor of the selector incoming line respectively the line characteristic frequencies and the busy condition frequency, the improvement which comprises identifying means associative with said selectors and adapted to effect selection of a desired outgoing line of an associated selector when free and to prevent selection thereof when busy, said identifying means comprising two thermionic amplifiers, means to apply to one of said amplifiers the voltages appearing on said talking conductor of the associated selector, means to apply to the other of said amplifiers a comparison voltage of a frequency characteristic of a desired outgoing line, said comparison voltage being supplied at such phase that it appears at the output to the other of said amplifiers substantially 180° out of phase with the voltage of the same frequency appearing at the output of the first of said amplifiers, a clipping tube coupled to the output of each of said amplifiers, a multigrid mixer tube capable of being cut off on either of two of its grids, means to couple separately the clipping tubes to the said grids of the mixer tube, a capacitor and a non-linear resistor in series connected in parallel with a resistor in the plate circuit of the mixer tube, a thermionic relay, means to couple the junction between the capacitor and non-linear resistor to a grid of the thermionic relay, means actuated by operation of the relay initiating a stopping of the selector movable scanning means, a tuned amplifier tuned to the busy condition frequency coupled to the busy test conductor of the selector incoming line, and means coupled to the output of the tuned amplifier responsive to the appearance of a signal thereon to disable the relay.

6. In a system of automatic telephony wherein each of a plurality of selectors includes for each of a plurality of outgoing lines connected thereto a fixed electrode energized at an A. C. voltage of a frequency characteristic of its line and movable means to scan capacitively the said electrodes and to transmit the line characteristic

voltages thereof to a talking conductor of the selector incoming line, and wherein each of a plurality of senders associative with the selectors of said plurality of selectors supplies upon call of a calling station for comparison a voltage of the frequency characteristic of a desired outgoing line cophasally with the voltage on the electrodes of that line in said selectors, each such sender including for the selection of such characteristic comparison frequencies a step-by-step rotary switch having a second row of contacts whose rotor blade is linked to the rotor blade of the characteristic comparison frequency selection contact row, the contacts of said second row being multiplied to corresponding contacts of other such senders available for association with selectors of the same stage, the improvement which comprises a plurality of identifying means separately associative with the said selectors, each identifying means of said plurality of identifying means serving to effect selection of a desired outgoing line of an associated selector when free and to prevent duplicate selection of the same outgoing line by other selectors of the same stage, each identifying means of said plurality of identifying means comprising two thermionic amplifiers of which one provides to the signal passed therethrough substantially 180° more phase change than the other provides to the signal passed through said other, means to apply to one of said amplifiers the voltages appearing on the said talking conductor of an associated selector, means to apply to the other of said amplifiers from an associated sender a comparison voltage of a frequency characteristic of a desired outgoing line of said associated selector, a clipping tube coupled to the output terminals of each of said amplifiers, a pentode mixer tube having its control and suppressor grids operated at zero bias and capable of being cut off on either of its two said grids, means to couple separately the clipping tubes to the control and suppressor grids of the mixer tube, a capacitor and a non-linear resistor in series connected in parallel with a resistor in the plate circuit of the mixer tube with the non-linear resistance adjacent the mixer tube plate and poled to permit a rapid charging of the capacitor during conduction in the mixer tube but to retard discharge of the capacitor when the mixer tube is cut off, a monostable multivibrator, means to couple the junction between the capacitor and non-linear resistor to a grid of the normally non-conducting tube in the multivibrator, means actuated by reversal in the conduction phase of the multivibrator to initiate a stopping of the movable scanning means in said associated selector, a multivibrator disabling-pulse generating multigrid tube biased to cut off on one of its grids and having its plate coupled to a grid of the normally non-conducting tube of the multivibrator, a duplicate-selection blocking tube operated at zero bias having its grid coupled to a second grid of the multivibrator disabling tube and having its plate coupled to a third grid of the multivibrator disabling tube and, via the multiplying contacts of the second row in the comparison frequency selecting switch of said associated sender, to the plates of the duplicate-selection blocking tubes of other identifying means of said plurality of identifying means instantaneously associated with senders effecting through selectors of the same stage selection of lines having the same characteristic frequency, and means operable upon reversal of the conduction phase in the

multivibrator to apply a negative pulse to the duplicate-selection blocking tube grid, whereby upon reversal of conduction phase in the multivibrator the multivibrator disabling tubes of said other identifying means are brought into conduction.

7. In a system of automatic telephony wherein each of a plurality of selectors includes for each of a plurality of outgoing lines connected thereto 10 two fixed electrodes of which a first one is energized at an A. C. voltage of a frequency characteristic of its line and of which the second is adapted to be energized when its line is busy by an A. C. voltage of a frequency characteristic of 15 the busy condition, each such selector including movable means to scan capacitively the said electrodes of its outgoing lines and to transmit to a talking conductor and to the busy test conductor of its incoming line respectively the line 20 characteristic frequencies and the busy condition frequency so scanned, and wherein each of a plurality of senders associative with said selectors is adapted to supply for comparison a voltage of the frequency characteristic of a desired outgoing line, each such sender including for the 25 selection of such characteristic comparison frequencies a step-by-step rotary switch having a second row of contacts whose rotor blade is linked to the rotor blade of the characteristic comparison frequency selection contact row, the contacts of said second row being multiplied to corresponding contacts of other such senders available for association with selectors of the same stage, the improvement which comprises a plurality of 30 identifying means separately associative with said selectors, each identifying means of said plurality of identifying means being adapted to effect selection of a desired outgoing line of an associated selector when free, to prevent selection 35 of said desired outgoing line when busy, and to prevent duplicate selection of the same outgoing line by other selectors of the same stage, each identifying means of said plurality of identifying means comprising two thermionic amplifiers 40 of which one provides to the signal passed therethrough substantially 180° more phase change than the other provides to the signal passed through said other, means to apply to one of said amplifiers the voltages appearing on the said talking conductor of an associated selector, means to apply to the other of said amplifiers from an associated sender a comparison voltage of a frequency characteristic of a desired outgoing line of said associated selector, said voltage 45 being at the input to the other of said amplifiers cophasal with the voltage of the same frequency appearing at the input to the first of said amplifiers, a clipping tube coupled to the output terminals of each of said amplifiers, a multigrid 50 mixed tube capable of being cut off on either of two of its grids, means to couple separately the clipping tubes to the said grids of the mixer tube, a capacitor and a non-linear resistor in series connected in parallel with a resistor in the plate 55 circuit of the mixer tube, a monostable multivibrator, means to couple the junction between the capacitor and non-linear resistor to a grid of the normally non-conducting tube in the multivibrator, means actuated by reversal in the conduction phase of the multivibrator to initiate a stopping of the movable scanning means in said associated selector, a tuned amplifier tuned to the busy condition frequency coupled to the busy 60 test conductor of the incoming line of said associated selector, means coupled to the output of 65

the tuned amplifier responsive to the appearance of a signal thereon to disable the multivibrator, a multivibrator disabling-pulse generating multigrid tube biased to cut off on one of its grids and having its plate coupled to a grid of the normally non-conducting tube of the multivibrator, a rectifier coupled across the output of the tuned amplifier and having its positive D. C. terminal connected to a grid of the multivibrator disabling tube, a duplicate-selection blocking tube operated at zero bias having its grid coupled to a second grid of the multivibrator disabling tube and having its plate coupled to a third grid of the multivibrator disabling tube, and, via the multiplying contacts of the second row in the comparison frequency selecting switch of said associated senders, to the plates of the duplicate-selection blocking tubes of other identifying means of said plurality of identifying means instantaneously associated with senders effecting through selectors of the same stage selection of lines having the same characteristic frequency, and means operable upon reversal of the conduction phase in the multivibrator to apply a negative pulse to the duplicate-selection blocking tube grid, whereby upon reversal of conduction phase in the multivibrator the multivibrator disabling tubes of said other identifying means are brought into conduction.

8. In a system of automatic telephony employing capacitive testing in line finding by means of selector scanning brushes moving past fixed electrodes and wherein a selector includes for each outgoing line connected thereto three fixed test electrodes of which one is energized from a source of A. C. voltage of a frequency characteristic of the tens digit of that line, of which a second is energized from a source of A. C. voltage of a frequency characteristic of the units digit of that line and of which the third is energized when that line is busy from a source of A. C. voltage of a frequency characteristic of the busy condition, and wherein a sender provides upon call of a calling station for comparison with the first two of said voltages A. C. voltages of frequencies characteristic of the tens and units digits of a desired line, said sender including for the selection of the units comparison voltage a multiple contact switch having a second set of contacts multiplied to the like contacts of all senders available for association with selectors of the same stage, the improvement which comprises identification means adapted to stop the selector on a desired outgoing line when free, to prevent its stopping on the desired outgoing line when busy, and to prevent other selectors of the same stage from making a conflicting selection of a desired line, said means comprising two thermionic amplifiers, a multigrid mixer tube having two of its grids operated at zero bias, means to apply the outputs of said thermionic amplifiers separately to said mixer tube grids, a two-time constant impedance including a capacitor and a non-linear resistor in series connected in parallel with a resistor, said impedance being connected in the plate circuit of the mixer tube, a monostable multivibrator having a grid of its normally non-conducting tube coupled to the junction between the capacitor and non-linear resistor, a normally cut off selector rotor stopping-pulse generator tube which when conducting generates on its cathode a positive pulse for application to the selector rotor stopping means and which generates simultaneously a negative pulse on its plate, a busy

75

signal amplifier tuned to the busy condition frequency, a multigrid multivibrator-blocking tube biased to cut off on one of its grids and having its plate coupled to a grid of the normally non-conducting tube of the multivibrator, a rectifier coupled across the output of the busy signal amplifier and having its positive D. C. terminal applied to the cut off grid of the multivibrator-blocking tube, a normally conducting duplicate-line selection blocking tube having a grid coupled to the plate of the selector rotor stopping-pulse generating tube and to a second grid of the multivibrator-blocking tube, a relay, a first contact on said relay connected when de-energized to couple one of said thermionic amplifiers to the tens digit A. C. voltage in the sender and when energized to couple the said one of the thermionic amplifiers to the units digit A. C. voltage in the sender, a second contact on said relay connected when de-energized to couple the other of said thermionic amplifiers to the selector rotor brush which scans the tens test electrodes of the selector outgoing lines and adapted when energized to couple the other of said thermionic amplifiers to the selector rotor brush which scans the units test electrodes of the second outgoing line, a third contact on said relay connected when de-energized to connect the plate of the normally conducting tube of the multivibrator to the actuating element of said relay and connected when energized to connect said plate to a grid of the selector rotor stopping-pulse generating tube, a fourth contact on said relay connected when energized to connect the busy test wire of the selector incoming line to the input of the busy signal amplifier, and a fifth contact on said relay connected when energized to connect the plate of the duplicate selection-blocking tube to the rotor blade of the second row of contacts in the units digit frequency selector of the sender.

9. In a system of automatic telephony employing capacitive testing in line finding by means of selector rotor scanning brushes moving past fixed stator electrodes and wherein each of a plurality of final selectors includes for each outgoing line connected thereto three fixed test electrodes of which one is energized from a source of A. C. voltage of a frequency characteristic of the tens digit of that line, of which a second is energized from a source of A. C. voltage of a frequency characteristic of the units digit of that line and of which the third is energized when that line is busy from a source of A. C. voltage of a frequency characteristic of the busy condition, and wherein each of a plurality of senders associable with such selector provides for comparison with the first two of said voltages A. C. voltages of frequencies characteristic of the tens and units digits of a desired line, all sources of voltage of the same frequency employed being cophasal, each such sender including for the selection of the units comparison voltage a step-by-step rotary switch having a second row of contacts multiplied to the like contacts of all senders available for association with selectors of the same stage, the improvement which comprises identification means adapted to stop the selector on a desired outgoing line when free, to prevent its stopping on the desired outgoing line when busy, and to prevent other selectors of the same stage from making a substantially simultaneous selection of a desired line, said means comprising two thermionic amplifiers of which one provides to the signal passed there-

through substantially 180° more phase change and the other provides to the signal passed through said other, a clipper stage coupled to the output of each of the two thermionic amplifiers, a pentode mixer tube having its control and suppressor grids operated at zero bias, means to apply the outputs of said clippers separately to said mixer tube grids, a two-time constant impedance including in series a capacitor and a non-linear resistor connected in parallel with a linear resistor, said impedance being connected in the plate circuit of the mixer tube with the non-linear resistor adjacent the mixer tube plate and being poled to permit a rapid charging of the capacitor when plate current flows in the mixer tube but to retard discharge of the capacitor when the mixer tube is cut off, a monostable multivibrator having a grid of its normally non-conducting tube coupled to the junction between the capacitor and non-linear resistor, a normally cut off selector rotor stopping-pulse generator tube which when conducting generates on its cathode a positive pulse for application to the selector rotor stopping means via the busy test wire of the selector incoming line and generates simultaneously a negative pulse on its plate, a busy signal amplifier tuned to the busy condition frequency, a pentode multivibrator-blocking tube biased to cut off on its control grid and having its plate coupled to a second grid of the normally non-conducting tube of the multivibrator, a rectifier coupled across the output of the busy signal amplifier and having its positive D. C. terminal applied to the control grid of the multivibrator-blocking tube, a normally conducting duplicate-line selection blocking tube having its grid operated at zero bias and coupled to the plate of the selector rotor-stopping pulse generating tube and to the suppressor grid of the multivibrator-blocking tube, a relay, a first contact on said relay connected when de-energized to couple one of said thermionic amplifiers to the tens digit A. C. voltage in the sender and when energized to couple the said one of the thermionic amplifiers to the units digit A. C. voltage in the sender, a second contact on said relay connected when de-energized to couple the other of said thermionic amplifiers to the selector rotor brush which scans the tens test electrodes of the selector outgoing lines and adapted when energized to couple the other of said thermionic amplifiers to the selector rotor brush which scans the units test electrodes of the second outgoing line, a third contact on said relay connected when de-energized to connect the plate of the normally conducting tube of the multivibrator to the actuating element of said relay and connected when energized to connect it to a grid of the selector rotor stopping-pulse generating tube, a fourth contact on said relay connected when energized to connect the busy test wire of the selector incoming line to the input of the busy signal amplifier, and a fifth contact on said relay connected when energized to connect the plate of the duplicate selection-blocking tube to the rotor blade of the second row of contacts in the units digit frequency selector of the sender.

10. In a system of automatic telephony including a plurality of selectors, a plurality of senders and a plurality of identifying means each adapted to stop an associated selector on an outgoing line thereof indexed by an associated sender, the outgoing lines of said selectors being multiplied together and the line indexing means

of said senders having contacts coupled thereto which are multiplied to like contacts of all of said senders, each of said identifying means including a relay adapted to generate a selector stopping signal upon identification of an outgoing line of an associated selector with the line indexed by an associated sender and further including a relay disabling amplifier actuable upon receipt by said identifying means from the associated selector of a signal indicating a busy condition for the desired outgoing line, the improvement which comprises means adapted to prevent duplicate selection of a single line by two of said selectors, said means including for each of said identifying means a duplicate selection blocking tube having its grid connected to a terminal of said relay experiencing a negative signal upon actuation thereof, said blocking tube having its plate coupled to a control grid of said relay disabling amplifier, said blocking tube having its plate coupled via the multiplying contacts of the sender associated with the identifying means of which said blocking tube is a part to the plates of corresponding blocking tubes of other identifying means of said plurality of identifying means instantaneously associated with senders indexed to the same outgoing line.

11. In a system of automatic telephony including a plurality of selectors, a plurality of senders and a plurality of identifying means each adapted to stop an associated selector on an outgoing line thereof indexed by an associated sender, the outgoing lines of said selectors being multiplied together and the line indexing means of said senders having contacts coupled thereto which are multiplied to like contacts of all of said senders, each of said identifying means including a relay adapted to generate a selector stopping signal upon identification of an outgoing line of an associated selector with the line indexed by an associated sender and further including a relay disabling amplifier actuable upon receipt by said identifying means from the associated selector of a signal indicating a busy condition for the desired outgoing line, the improvement which comprises means adapted to prevent duplicate selection of a single line by two of said selectors, said means including for each of said identifying means a duplicate selection blocking relay adapted to be actuated upon selection of the line by a selector associated with the identifying means of which said duplicate selection blocking relay is a part, said duplicate selection blocking relay being coupled to a control grid of the relay disabling amplifier of its own identifying means and, via the multiplying contacts of its associated sender, to the plates of corresponding duplicate selection blocking relays of other identifying means of said plurality of identifying means instantaneously associated with senders indexed to the same outgoing line, whereby upon selection of an outgoing line by one of said selectors the duplicate selection blocking relays of other selectors of said plurality of selectors instantaneously associated with senders indexed to the same outgoing line are actuated.
